Primary Examiner—Ted Shooman
Assistant Examiner—Nanda Bondade
Attorney, Agent, or Firm—Michael N. Meller

[73] Assignee: **Teac Corporation**, Tokyo, Japan

[57] **CLAIM**
The ornamental design for a combined digital audio disc
player, radio tuner, amplifier and tape recorder, as shown and
described.

[21] Appl. No.: 56,322

DESCRIPTION

[22] Filed: **Jun. 26, 1996**

Foreign Application Priority Data

Dec. 28, 1995 [JP] Japan 7-40045

FIG. 1 is a front view of a combined digital audio disc
player, radio tuner, amplifier and tape recorder showing our
new design;

[51] LOC (6) Cl. 14-01

FIG. 2 is a rear view thereof;

[52] U.S. Cl. D14/168

FIG. 3 is a top view thereof;

[58] Field of Search D14/124, 156,

FIG. 4 is a bottom view thereof;

D14/160, 164-165, 168-171, 188, 193-195,
197-198; 455/344, 350, 351

FIG. 5 is a right side view thereof;
